ENDLESS TRACK TOOL

Frank J. Jakoubek, Elmwood Park, and William E. Gahl, Berwyn, Ill., assignors to Templeton, Kenly & Co. Inc., Chicago, Ill., a corporation of Illinois

Application January 9, 1943, Serial No. 471,912

14 Claims. (Cl. 59—7)

1

This invention relates to improvements in endless track tools and it consists of the matters hereinafter described and more particularly pointed out in the appended claims.

One form of the endless track employed in the heavier tractors, military tanks and the like, include plate-like traction shoes having trunnions projecting from the ends of each side thereof to receive bearing sleeves on connector plates that operatively connect the end of adjacent shoes together. When a breakage occurs in such a track that requires a repair or replacement of a part thereof, great difficulty is encountered not only in pulling a connector plate off its trunnions, but in drawing the broken end of the track together into such position that a new connector plate may be applied. We are aware that certain tools are available for each purpose, but these are open to a number of objections which it is the purpose of this invention to overcome.

One of the objects of the present invention is to provide a strong, light weight tool that may be readily handled by one man and which may be used either to pull a connector plate from the track or to draw the broken ends of the track together into that position making it an easy matter to apply a new connector plate.

Also, it is an object of the invention to provide a tool of this kind which is compact in size so as to take up but little carrying space and which has its parts so arranged and correlated that the screw employed therein is relieved or guarded against buckling or bending in use and so that the tool cannot bind or jam but will always remain in a good operating condition.

The above mentioned objects of the invention, as well as others, together with the advantages thereof will more fully appear as the specification proceeds.

In the drawings:

Fig. 1 is a top plan view of a part of an endless track structure showing the use of a pair of the improved tools in pulling the broken ends of such a track structure together into that position permitting the application of a connector plate thereto.

Fig. 2 is a side elevation of the parts shown in Fig. 1.

Fig. 3 is a fragmentary top plan view of a part of an endless track structure with one of the improved tools in position thereon for pulling a connector plate therefrom.

Fig. 4 is a side elevation of the parts shown in Fig. 3.

Fig. 5 is a view in elevation of the left hand

2

end of the tool appearing in Fig. 2 on a somewhat enlarged scale.

Figs. 6 and 7 respectively are transverse vertical sectional views on the scale of Fig. 5, as taken on the lines 6—6 and 7—7 of Fig. 2.

Figs. 8 and 9 respectively are perspective views of a pair of block-like elements forming a part of the tool and which will be more fully referred to later.

10 Fig. 10 is a view in side elevation of a modified form of parts appearing at the left hand side of Fig. 4.

15 Referring now in detail to that embodiment of the invention illustrated in the drawings, Figs. 1 and 2 illustrate one form of endless track structure with which the improved tool may be readily used. Such a track structure includes a plurality of rectangular plate-like shoes 10—10, each formed at each side thereof with a pair of 20 outwardly projecting trunnions 11—11. Adjacent shoes of the structure are connected together at both sides by means of end connectors 12—12. Each connector includes a driving or 25 traction lug 13 and a pair of open ears 14—14 projecting laterally from one face thereof. Each ear is adapted to operatively receive a trunnion 11—11 which is journalled therein and said ears are connected together by a web 15 which has a hole 16 therein (see Fig. 2), the purpose of which 30 will later appear.

35 The improved tool, which is indicated as a whole at 20 includes a pair of parallel edgewise disposed relatively long bars or rails 21—21 providing a duplex beam. Between one end of said bars, which for convenience is termed the actuating end of the tool, is located a spacer block 22 which has recesses 23 (see Fig. 7) in its sides, each to receive the associated end of the bars. A bolt 24 passes through the bars and a part of the 40 block and holds said parts together in operative relation. The block 22 is provided in its upper portion with a hole 25 (see Fig. 7) in which is journalled a part 26 of a relatively long screw 27. Said screw part 26 extends outwardly beyond 45 the ends of the bars where a bifurcated socket 28 is journalled thereon. Between the spaced arm 28a of the socket is located a ratchet wheel 29 that is fixed to the screw part 26 and a washer and pin assembly 30 is provided on the extremity 50 of said screw part to hold the parts in position. The screw 27 is provided adjacent the block 22 with an annular shoulder 31 and between this shoulder and the inner face of the block 25 is a thrust bearing 32. The socket is formed at its 55 free end to receive an actuating lever 33 and

there carries a finger lug 33a. The socket also carries a reversible pawl 34 to coast with the ratchet wheel so that the screw may be turned step by step in either direction, as is well known.

The opposite end of the bars 21-21 engage in recesses 35-35 in the sides of a block member 36, best shown in perspective in Fig. 8. A transverse bolt 37 passes through the parts mentioned whereby the said member 36 and the bars 21-21 are rigidly connected together. The block member 36 is provided with a bottom extension 38 and in the front face thereof is a recess 39. A hole 40 (see Fig. 8) is provided in the extension below the recess and this hole lines up with a recess 41 (see Fig. 2) in the block member above the recess. At one side of the block member 36 and rising from the top surface thereof is a hook 42 that faces in a direction opposite the recess 39. In the upper central part of the body of the block member is a threaded longitudinal hole 43 (see Fig. 8) which receives a bolt-like adjusting stem or member 44. Associated with the bolt 37 is a nut 46 which secures an eared plate 47 to the bars. This eared plate has one end of a chain 48 fixed thereto and the other end of which is connected to one end of a pin 49 that may be inserted up through the opening 40 into the recess 41 in the block member 36 for a purpose soon to appear. When said pin is not disposed in said opening and recess respectively, it hangs from the tool as a whole, by means of the chain and will not readily become lost.

50 indicates a second block-like member that has a sliding guided engagement on the rails 21 between the blocks 22 and 36 that are fixed to said rails. The block-like member 50, which best appears in perspective in Fig. 9, is provided in its opposite sides with grooves 51-51 which fit and receive the inner sides of the rails 21-21. This permits the block to slide on the rails, but prevents the displacement of said block with respect to said bars. Centrally in the upper portion of the body of the block-like member 50 is a threaded hole 52 (see Fig. 9) in which the screw 27 has a threaded engagement. Rising on one side of the top of said block-like members 51 is an upstanding hook 53 which when the parts before described are assembled, faces the hook 42 of the block like member 36. Said block-like member 50 is flanged laterally at the bottom as indicated at 54 and secured as by welding to said bottom is a pair of laterally spaced stems 55. These stems have a diameter approximating that of the trunnions 11-11 of the track structure and are spaced apart to coincide with the spacing between the axis of the ears 14-14 of the connector plates 12. With said stems so spaced, they are capable of straddling the extension 38 of the block member 36 when the block member 50 is in one position with respect to said block member 36.

When it is necessary to pull a connector plate 12 from the plate trunnions 11 upon which it is mounted, only one tool is employed, as appears in Figs. 3 and 4, and when it is necessary to draw the shoes of the track structure at opposite sides of a break therein, two tools are employed, as appears in Figs. 1 and 2. In removing a connector plate, the following procedure may be followed.

Assume that the pin 49 has been pulled out of the hole 40 and recess 41 in the block member 36 and is hanging therefrom by means of the chain 48. The tool as a whole is thus disposed perpendicular to the side of the track structure with

the block member 36 facing the same. The tool is then moved in toward the track structure so that the recess 39 of the block member 36 straddles the web 15 of the connector plate to be pulled and so that the hole 40 and recess 41 in said member line up with the hole 16 in said web of said connector plate. The pin 49 is then inserted up through the hole 40 in the block and is passed through the hole 16 in the web of the connector plate 12 operated upon and into the recess 41 of said block member. The bolt-like stem 44 is then turned by the fingers until its free end engages the lug 13 of the connector plate.

The socket 28 is now turned in that direction which will, through the screw 27, cause the block-like member 50 to be moved along the rails 21-21 toward the block-like member 36 until the stems 55 engage the ends of the trunnions 11-11 disposed in the sleeves 14-14 of the connector plate. This limits the movement of the block member 50 toward the track structure. Further turning movement of the socket 28 causes the rest of the tool to move outwardly away from the track structure because the stems 55 now act as stops. In said further turning movement of the socket, as the connector plate is fixed to the block member 36 by the pin 49, a pulling force is transmitted therethrough to pull the connector plate off the trunnions 11-11. With the bolt or screw-like stem 44 engaged with the lug of the connector plate, the pulling action cannot crook or twist the tool as a whole and cause it to swing about an axis as provided by the engaged ends of the stems 55 and trunnions 11. It will be noted that the bolt or screw-like stem 44 is substantially aligned with the screw 27 and therefore a steady pull in a direction parallel with the axis of the trunnions 11-11 is afforded and this without causing the connector plate to bind on said trunnions or pins.

As before mentioned, to draw two adjacent broken ends of the track structure together into operative relation, two tools are employed, one on each side of the structure at the break as shown in Fig. 1. In carrying out this operation, the tool is manipulated to back the block-like member 50 away from the block-like member 36 a distance somewhat greater than the distance between the two ends of the track structure at the break.

The hook 42 of the block 36 of one tool 20 is first engaged with a trunnion 11 at one side of the structure at the break. By turning the socket 28 in the proper direction, the block 50 is caused to move along the rails 21-21 until its hook 53 engages the trunnion at the other end of the break. By reason of the engagement of the hooks with said trunnions, the tool is now supported along one side of the track structure and substantially parallel therewith. The other tool 20 is applied and attached in place in the same way to the track structure at the other end of the break. If only one man is at work, he first turns the socket 28 of one tool and then the socket 28 of the other tool step by step. This causes the blocks 36 and 50 of both tools to approach each other and by reason of the engagement the hooks 42 and 53 have with said trunnions 11-11 at both sides of the shoes at the break, the shoes are drawn toward each other until they reach the position where the trunnions 11-11 are disposed so that a connector plate 12 may be applied thereto. It is to be noted from Fig. 1 that the hooks 42 and 53 of the block members 36 and 50 are disposed adjacent the sides of the shoes and that the free ends of the engaged trunnions

11—11 extend outwardly beyond the sides of the hooks so as to permit them to enter the sleeves 14—14 of the connector plate being applied. After the connector plates have been initially applied as above mentioned, they hold the shoes together so that both tools 20—20 may be removed from the track structure simply by turning the sockets 28 of said tools in the other direction to back the block members 50 away from the block members 36. The connector plates 12—12 may now be driven home into position on the trunnions to be pinned thereto in the usual manner.

It is pointed out that with the construction described, the axis of the screw 27 is disposed quite close to the line of resistance as imposed upon the tool by the engagement with the trunnions 11—11 at the break in the track structure. This arrangement in connection with the use and position of the bolt-like stem 44 so closely to the line of force developed in the operation of the tool, not only prevents the tool from crooking or twisting out of place to jump off the engaged trunnions due to the said application of force but also prevents tipping of the connector plate and binding upon its trunnions 11—11. Another feature of advantage is that by the edgewise arrangement of the bars 21—21, they function as a duplex beam able to resist all buckling pressures or forces and protect the screw 27 against such forces so that it remains straight and true. Therefore the block member 50 can never bind upon said screw so that a freely operating tool is had at all times. Also, it is to be noted that the bars 21—21 protect the screw from being nicked or injured while in a box with other tools and this too assists in affording a free operating tool because there will be no burrs on the threads of the screw to cause a binding of the block member 50 thereon.

Instead of employing the pin 49 and its associated chain 48 as and for the purpose before described, we may employ the arrangement shown in Fig. 10 thereby simplifying the structure by eliminating the chain 48, member 47 and the bottom extension 38 on the block member 36. To do this we employ a pin 49^a having a pressed in fit in the block member 36 so that a part of said pin projects below the block member 36. This part of the pin then acts as a downwardly facing hook that is entered into a hole 16 in the mid portion of the connector plate from above. With said part of the pin, which is relatively short, disposed in said hole, the tool is operated as before described and the connector plate is slowly and steadily pulled from its associated trunnions.

While in describing the invention we have referred in detail to the form, arrangement and construction of the parts involved, the same is to be considered only in the illustrative sense and therefore we do not wish to be limited thereto except as may be specifically set forth in the appended claims.

We claim as our invention:

1. A tool of the kind described and embodying therein means providing a rigid beam, block-like members mounted on said beam for a relative longitudinal movement thereon, one of said members carrying a part for detachable engagement with a part of the connector plate mounted on adjacent trunnions of an endless track structure, a pair of laterally spaced projecting members carried by the other member and positioned in alignment with and adapted to engage said trunnions, when said other member moves toward the first mentioned one, means for producing said

relative movement between said block-like members, and means carried by said one of said block-like members for engaging another part of said connector plate to prevent tipping thereof when said laterally spaced projecting members engage said trunnions.

2. A tool of the kind described and embodying therein means providing a rigid beam, a pin-like part fixed with respect to one end of the beam and adapted to be detachably engaged in an opening in a part of the connector plate of an endless track structure having trunnions upon which said plate is operatively engaged, a block-like member mounted on said beam for longitudinal movement thereon toward and away from said one end of the beam, means carried by said block-like member and adapted for engagement with said trunnions as said block-like member moves toward said one end of the beam, and means for imparting movement to said block-like member on said beam toward and away from said one end of the beam.

3. A tool of the kind described and embodying therein means providing a rigid beam, block-like members mounted on said beam for a relative longitudinal movement thereon, one of said members having a part to embrace a part of the connector plate mounted on adjacent trunnions of an endless track structure, means for detachably securing said parts together when one embraces the other, means carried by the other of said members and adapted for engagement with said trunnions, means for producing said relative movement between said block-like members, and means adjustably engaged with said first mentioned block-like member and adapted for engaging another part of said connector plate for preventing tipping thereof when said means carried by said last mentioned block-like member engages said trunnions.

4. A tool of the kind described and embodying therein a pair of laterally spaced rail members, a block-like member disposed between and secured to one end of said rail members, a second block-like member disposed between and having sliding guided engagement on said rails toward and away from the first mentioned member, said first mentioned member carrying a pin-like part adapted to be detachably engaged in an opening in a part of the connector plate engaged upon a pair of trunnions of an endless track structure, means carried by the second block-like member and adapted for engagement with said trunnions when said second block-like member is moved toward the first mentioned one, and means for moving the second block-like member toward and away from the first mentioned one.

5. A tool of the kind described embodying therein means providing a beam, means for detachably connecting one end of said beam to a connector plate mounted on a pair of spaced trunnions on adjacent shoes of an endless track structure, a member mounted on said beam for movement toward and away from said end of the beam and carrying parts arranged below said beam and extending toward said end thereof, said parts being spaced to engage the ends of said trunnions when said member is moved toward said end of the beam, and means for moving said member on said beam toward and away from said end thereof.

6. A tool of the kind described embodying therein means providing a beam, means for detachably connecting one end of said beam to a connector plate mounted on a pair of spaced

trunnions on adjacent shoes of an endless track structure and which connector plate includes a traction lug, a member mounted on said beam for movement toward and away from said end and carrying parts extending toward said end of the beam and spaced to engage the ends of said trunnions when said member is moved toward said end of the beam, means carried by said end of the beam for engaging said traction lug when said parts exert a pushing force against said ends of said trunnion to prevent tipping of said connector plate, and means for moving said member on said beam toward and away from said end thereof.

7. A tool of the kind described embodying therein means providing a beam, means for detachably connecting one end of said beam to a connector plate mounted on a pair of spaced trunnions on adjacent shoes of an endless track structure and which connector plate includes a traction lug, a member mounted on said beam for movement toward and away from said end and carrying parts extending toward said end of the beam and spaced to engage the ends of said trunnions when said member is moved toward said end of the beam, means carried by said end of the beam for engaging said traction lug when said parts exert a pushing force against said ends of said trunnions to prevent tipping of said connector plate, said last mentioned means being adjustable in length longitudinally of the beam, and means for moving said member on said beam toward and away from said end thereof.

8. A tool of the kind described, embodying therein means providing a beam, means providing a depending projection on one end of the beam for detachable engagement in an opening in a connector plate mounted on a pair of spaced trunnions on adjacent shoes of an endless track structure, a member mounted on said beam for movement toward and away from said end of the beam and carrying parts extending toward said end of the beam and spaced to engage the ends of said trunnions when said member is moved toward said end of the beam, and means for moving said member on said beam toward and away from said end thereof.

9. A tool of the kind described, embodying therein means providing a beam, means providing a depending projection on one end of the beam for detachable engagement in an opening in a connector plate mounted on a pair of spaced trunnions on adjacent shoes of an endless track structure, and which connector plate includes a traction lug, a member mounted on said beam for movement toward and away from said end and carrying parts extending toward said end of the beam, means carried by said end of the beam for engaging said traction lug when said parts exert a pushing force against said ends of said trunnions to prevent tipping of said connector plate, and means for moving said member on said beam toward and away from said end thereof.

10. A tool of the kind described, embodying therein a beam including a pair of laterally spaced bars, a member connecting the bars at one end of the beam together, means carried by the member at said one end of said beam for detachably connecting said end of the beam to a connector plate mounted on a pair of spaced trunnions on adjacent shoes of an endless track structure, a block-like member mounted on said bars for movement toward or away from said member at said one end of the beam and carrying parts that extend toward said end of the

beam and which parts are spaced to engage the ends of said trunnions when said block-like member is moved toward said end of the beam, and means for moving said block-like member on said beam toward and away from said one end thereof.

11. A tool of the kind described, embodying therein a beam including a pair of laterally spaced bars, a member connecting the bars at one end of the beam together, means carried by the member at said one end of said beams for detachably connecting said end of the beam to a connector plate mounted on a pair of spaced trunnions on adjacent shoes of an endless track structure, and which connector plate includes a traction lug, a block-like member mounted on said bars for movement toward and away from said member at said one end of the beam and carrying parts that extend toward said one end of the beam and which parts are spaced to engage the ends of said trunnions when said block-like member is moved toward said end of the beam, means carried by said member at said one end of the beam for engaging said traction lug when said parts exert a pushing force against said ends of said trunnions to prevent tipping of said connector plate, and means for moving said block-like member on said beam toward or away from said end thereof.

12. A tool of the kind described embodying therein a beam including a pair of laterally spaced bars, a member connecting the bars at one end of the beam together, means carried by the member at said one end of said beams for detachably connecting said end of the beam to a connector plate mounted on a pair of spaced trunnions on adjacent shoes of an endless track structure, and which connector plate includes a traction lug, a block-like member mounted on said bars for movement toward and away from said member at said one end of the beam and carrying parts that extend toward said one end of the beam and which parts are spaced to engage the ends of said trunnions when said block-like member is moved toward said end of the beam, means carried by said member at said one end of the beam for engaging said traction lug when said parts exert a pushing force against said ends of said trunnions to prevent tipping of said connector plate, said last mentioned means being disposed above said means carried at said one end of said beam for detachably connecting the same to said connector plate and being adjustable longitudinally of said beam, and means for moving said block-like member on said beam toward or away from said end thereof.

13. A tool of the kind described embodying therein a beam, a member fixed to one end of said beam, a second member mounted on the beam for longitudinal guided movement toward and away from the first mentioned member, a pair of laterally spaced trunnion engageable stems carried by said second member below and arranged parallel with the beam and facing the first mentioned member, means carried by the first mentioned member and disposed in a plane between the planes of said stems and adapted for detachable engagement with a part of a connector plate, and means carried by the beam and engaged with the second member and operable to move the same longitudinally of the beam toward and away from the first mentioned member.

14. A tool of the kind described embodying therein, a beam including a pair of laterally

spaced rails, a block-like member fixed between one end of said rails, a second block-like member fixed between the other end of said rails, a third block-like member disposed between the mid portions of said rails and having a guided engagement therewith for movement thereon toward either one of the first two mentioned block-like members, a part of said third block-like member depending below said rail, a pair of laterally spaced trunnion engageable stems fixed to said part of the third block-like member and arranged parallel with said rails and extending toward the first mentioned block-like member, means carried by the first mentioned block-like member and disposed in a plane between the planes of said stems and adapted for detachable engagement with a part of a connector plate, and means disposed between said rails and engaged with said second and said third mentioned block-like members and operable to move said third

mentioned block-like member toward or away from either the first or the second mentioned ones of said block-like members.
